FOREIGN PATENT DOCUMENTS

CN 104717903 B 9/2017

Primary Examiner — Mary Ann Calabrese*(74) Attorney, Agent, or Firm* — Price Heneveld LLP(57) **CLAIM**

We claim the ornamental design for a table, as shown and described.

DESCRIPTION

FIG. 1 is a front perspective view of a table;
 FIG. 2 is a bottom perspective view thereof;
 FIG. 3 is a front elevation view thereof, the rear elevation view being identical;
 FIG. 4 is a right-side elevation view thereof, the left side elevation view being identical;
 FIG. 5 is a top plan view thereof;
 FIG. 6 is a bottom plan view thereof; and,
 FIG. 7 is a cross-sectional view along VII-VII of FIG. 3.
 The broken lines in FIGS. 1-7 illustrate environmental features that form no part of the claimed design.

1 Claim, 7 Drawing Sheets---
